UNITED STATES PATENT OFFICE.

SAMUEL M. LANGSTON, OF WENONAH, NEW JERSEY, ASSIGNOR TO SAMUEL M. LANGSTON COMPANY, OF CAMDEN, NEW JERSEY, A CORPORATION OF NEW JERSEY.

SHEET FEEDING AND STACKING MECHANISM.

1,214,188.

Specification of Letters Patent. Patented Jan. 30, 1917.

Application filed February 10, 1915. Serial No. 7,243.

To all whom it may concern:

Be it known that I, SAMUEL M. LANGSTON, a citizen of the United States, and resident of Wenonah, in the county of Gloucester and State of New Jersey, have invented certain new and useful Improvements in Sheet Feeding and Stacking Mechanism, of which the following is a specification.

My invention relates to mechanism for feeding sheets, thin boards, corrugated paper, or the like, to a machine and for receiving and stacking the sheets as they come from the machine. The character of the operation performed upon the sheets while passing through the machine is immaterial as it may involve printing, embossing, scoring, perforating or the like.

Merely for purpose of illustration and to facilitate a clear understanding of my invention and of the construction and operation of one embodiment thereof, I will describe it in connection with a printing press, but I do not desire to be in any way limited to either the details of the press or the use of my invention in connection with a printing press.

My invention relates particularly to that type of feeding mechanism in which a column or stack of sheets is disposed upon a vertically movable support which may be raised to maintain the top of the stack or column at a substantially constant level or elevation as successive sheets are fed from the top of the stack or column.

In my prior application, Serial No. 853,012, filed July 25, 1914, I have illustrated and claimed a sheet feeding mechanism in which a stack is automatically raised each time a sheet is fed therefrom and for a distance substantially equal to the thickness of the sheet so as to maintain the top of the column at an approximately constant elevation. This necessitates a readjustment of the machine each time sheets of a different thickness are to be fed.

One object of my present invention is to automatically govern or control the stack elevating mechanism so that the top of the stack or column may be automatically maintained at the desired elevation, irrespective of variations in the thickness of the stock. In its preferred embodiment, this mechanism involves detachable connections between the source of power and the elevating mechanism, *per se*, and means controlled

by the height of the top of the column for rendering the said connections operative or inoperative. Thus, as successive sheets are fed from the top of the stack at a uniform rate, the support for the stack will rise at such times and at such rates as may be necessary for insuring the top of the stack at the proper elevation in respect to the receiving portion of the machine.

A further important feature involves the automatic controlling of the lowering of the support for the stack at the delivery end of the machine at a rate dependent upon the rate of accumulation of the sheets upon said stack. As the sheets come from the machine, they are automatically piled up in a stack on a vertically movable support and this support is lowered at a constant or variable rate, as occasion may demand, in order that the top of the stack may always bear the desired relationship to the delivery mechanism of the machine.

I have illustrated one embodiment of my invention in connection with a machine having a stack elevating mechanism invented by me and constituting the subject matter of my prior application, Serial No. 853,012, filed July 25, 1914, and in the same machine I have illustrated a controller or gage mechanism for preventing the delivery of more than one sheet at a time to the machine and which mechanism was invented by me and forms the subject matter of my Patent No. 1,174,739, of March 7th, 1916. I do not here claim the details of these mechanisms. I desire it to be specifically understood that my present invention is not limited for use solely in connection with the specific machine illustrated in my application and patent above referred to, but may be used in connection with various other forms of sheet feeding, controlling and stacking mechanisms.

I desire the specific machine, shown in the accompanying drawings, to be considered in an illustrative, rather than in a limiting sense. Reference is to be had to these drawings in which similar reference characters indicate corresponding parts in the several views and in which,

Figure 1 is a side elevation of a machine constructed in accordance with my invention, Fig. 2 is a side elevation, on an enlarged scale, of a portion of the machine shown in Fig. 1 and with parts broken

away, and Fig. 3 is a perspective view of a portion of the machine including the circuit closer.

I have illustrated my invention in connection with a printing press having type and impression rollers 10 and 11 between which sheets of paper may be fed from a supply stack A to a receiving stack B. The supply stack A of sheets to be fed to the feed rollers 12 of the machine, rests upon a suitable support in the form of a pair of bars 13, and cables 14 and 15 extend from the ends of these bars over pulleys 16 and 17 to one or more winding drums 18 on a shaft 19. Power is transmitted from the shaft of the impression roller 11 by a chain 20 to a shaft 21 carrying a crank arm 22. A rod 23 connects the crank arm to a lever 24 pivoted on a shaft 25. The shaft also carries a ratchet wheel 26 and a hand wheel 27 and the lever 24 carries a pawl 28 engaging with the ratchet wheel. The shaft of cylinder 11 is continuously rotated at a uniform speed and causes the rod 23 to reciprocate and the lever 24 or arm 24 to swing back and forth. The pawl, in engaging with the ratchet wheel 26, causes rotation of the shaft 25 when moving in one direction and permits the shaft to remain at rest when moving in the reverse direction. The range of movement of the pawl may be varied by varying the eccentricity of the pivotal connection between the arm 22 and the rod 23. The shaft 25 is thus intermittently rotated but its rate of rotation may be varied. Suitable gear mechanism is employed for transmitting this intermittent rotation from the shaft 25 to the winding drum 18. For instance, the shaft 25 may have a worm engaging with a worm wheel 30 mounted on the shaft 31 and the latter may transmit motion to the shaft 19 by a pair of intermeshing bevel gears. By means of this mechanism, all of which was clearly disclosed in my prior application, Serial No. 853,012, I am able to secure a very slow rotation of the cable winding drums and the slow elevation of the stack.

The feeding mechanism is illustrated as including a swinging arm 33 pivotally mounted at the upper end of a standard 34 and swung by the engagement of a cam 35 with the end of an arm 36 rigid with the arm 33. The arm 33 at its lower end carries a hook or catch 37 which engages with the rear edge of the top sheet and advances it toward the feeding rollers 12 of the machine.

I am able to vary the rate of stack elevating movement in respect to the rate of operation of the machine and the rate at which the sheets are fed from the top of the stack, by varying the eccentricity of the point of connection of the arm 22 and rod 23. A stack of sheets of uniform thickness may be maintained with the top at a constant ele-

vation, but experience shows that sheets of heavy card-board, paper board, or corrugated paper vary slightly in thickness and also it is often necessary to feed sheets of various different thicknesses which necessitates a change in the adjustment of the machine for each kind of sheet. By means of my present invention, I am able to automatically govern the relative rates of rotation of the winding drums and the impression rollers and thus automatically maintain the desired elevation of the top sheet irrespective of variations in the thicknesses of sheets in a single stack and irrespective of complete changes in the character of the stock and thicknesses of the sheets being fed. To secure this result, I provide an electro-magnet 49 on an extension of the lever or arm 24 and adjacent to the pawl 28 and so form the pawl and magnet that when the magnet is energized it will lift the pawl and hold it out of engagement with the ratchet wheel and permit the lever 24 to swing back and forth in either direction without effecting any rotation of the ratchet wheel. When the circuit is broken, the pawl may drop back into engagement with the ratchet and will rotate the latter when moving in one direction and slip over the teeth when moving in the opposite direction.

For making and breaking the circuit, I may provide any one of various different forms of circuit closers operated or controlled by variations in the level of the top of either the stack A or the stack B. In the accompanying drawings, I have illustrated a machine having a gage or controlling device vertically movable with variations in the elevation of the top of the stack. This mechanism includes a rod 45 vertically movable within guides 46 and 47 and having at its lower end a roller 48 adapted to rest upon the top of the stack. Incidentally this roller in moving up and down varies the elevation of a pair of gage members 49 and 50, and the gage members and roller are counterbalanced by a weight 51 connected to the vertically movable rod and the parts supported thereby by a cable 52 passing over a pulley 53. The roller 49 and rod 45 rise and fall with variations in the elevation of the top sheet, and I utilize this movement for controlling the electric circuit of the electro-magnet.

As shown, I mount on a frame member 55 of the machine, a pivoted contact member 56 in the path of a contact member 57 carried by and insulated from the rod 45. The contact member 57 is normally below the contact member 56 and the latter is free to move vertically a limited distance with the contact member 57. If the feeding mechanism be operating to raise the stack faster than the sheets are being fed therefrom the contact member 57 will engage with the 130

contact member 56 and thus close the electric circuit of the magnet 40. This will raise the pawl 28 out of engagement with the ratchet wheel 26 and the vertical movement of the stack support will be interrupted. The operation of the mechanism for feeding sheets from the top of the column will not be interrupted, nor will the operation of the machine itself. As soon as a sufficient number of sheets have been fed off from the top of the column so as to lower the level to such a point that the contact member 57 no longer engages with the contact member 56, the circuit will be broken, the pawl 28 will be released, and the slow elevating of the stack support will again begin. In this way the top of the stack is held within very narrow limits at all times and it is unnecessary for the workman or attendant to pay any attention to the operation of this portion of the machine.

Although I have shown the connection between the crank arm 22 and the rod 23 as being adjustable so as to vary the rate of feed, it is evident that this adjustment may be eliminated and the variation in the rate of feed secured solely by moving the pawl 28 into and out of operative position.

As a further important feature of my invention, I substantially duplicate the support for the stack A at the delivery end of the machine and utilize it for supporting a stack B of the sheets delivered from the machine. The support is in the form of two rods 60 connected by cables 61 and 62 passing over suitable pulleys 64 to one or more winding drums 63. The winding drum 63 is preferably made substantially the same size as the winding drum 18 and the two drums are connected by suitable gearing so as to rotate simultaneously at the same rate and in the same direction. This gearing as shown includes a chain 65 passing over sprocket wheels on the shafts of the winding drums. Thus, as the winding drums 18 rotate to elevate the stack A, the winding drums 63 will rotate to lower the support for the stack B at the same rate and to the same extent. As each sheet removed from the stack A eventually reaches the top of the stack B, it is evident that variations in the elevation of the top of one stack will

correspond to variations in the elevation of the top of the other stack, and as the stack elevating mechanisms are connected to operate simultaneously, it is evident that the making and breaking of the circuit will control the lowering of the stack B. It is also evident that the mechanism for rotating the winding drums may be connected to and act directly upon the shaft of the drum 63 instead of the shaft of the drum 18 and that the circuit closer instead of being mounted adjacent to and controlled by the position of the top of the stack A, may be mounted adjacent to and controlled by the position of the top of the stack B.

Various other changes may be made in the positioning and construction of my improved attachment, and the attachment may be employed in connection with various other forms of stack elevating and lowering mechanism from that shown.

Having thus described my invention, what I claim as new and desire to secure by Letters Patent, is:

In combination, a stack support, a ratchet wheel, connections between said ratchet wheel and said support for raising the latter upon the rotation of said ratchet wheel in one direction, oscillating means for feeding sheets from said stack, a pivoted arm, a pawl carried by said arm and adapted to engage with said ratchet wheel, a link connected to said arm, means operating in conjunction with said oscillating feeding means to oscillate said link and pawl, means for varying the range of movement of said link and pawl in respect to the range of movement of said feeding means, an electromagnet carried by said arm adjacent to said pawl and adapted when energized to hold said pawl out of engagement with said ratchet wheel, and means controlled by the elevation of the top of the stack for controlling the circuit of said electromagnet.

Signed at New York city in the county of New York and State of New York this 9th day of February A. D. 1915.
